WARP KNITTING MACHINE

Fritz Lambach, Tenafly, N. J., assignor to Robert Reiner, Inc., Weehawken, N. J.

Application June 29, 1950, Serial No. 171,051

31 Claims. (Cl. 66—86)

1

The present invention relates to knitting machines, and more particularly to warp knitting machines having a plurality of guide bars, each carrying a row of warp guides.

In order to be able to thread warp yarns through the eyelets of warp guides carried by the rear guide bar, it is necessary to lift a guide bar or guide bars arranged in front of said rear guide bar.

An object of the present invention is to provide a warp knitting machine equipped with an apparatus for lifting the front guide bar or guide bars, which may be readily operated.

Another object of the present invention is to provide a warp knitting machine, wherein the mechanism for lifting the front warp guide bar or guide bars may be operated from any place along the machine, so that for example in case of warp yarn breakage the attendant may operate the lifting mechanism from a position in front of the location of the warp yarn breakage, wherever said location may be.

A further object of the present invention is to provide a warp knitting machine equipped with safety devices preventing an operation of the main motor of the machine when the liftable guide bar or guide bars are in an elevated position and preventing a not intended lifting of the guide bar or guide bars when the main motor is running.

Another object of the present invention is to provide an efficient electrical system for the displacing of the liftable guide bar or guide bars of the warp knitting machine.

A further object of the present invention is to provide an electrical system for the control of the main motor of the warp knitting machine and of the electrical means for displacing the liftable guide bar or guide bars, which electrical system includes safety means preventing an operation of the main motor when the guide bar or guide bars are lifted and preventing an operation of the electrical means for lifting of the guide bar or guide bars when the main motor is running.

Another object of the present invention is to improve on the art of warp knitting machines as now ordinarily made.

Other objects and structural details of the invention will be apparent from the following description when read in conjunction with the accompanying drawings forming part of this specification, wherein:

Fig. 1 is a somewhat diagrammatical side elevational view of a warp knitting machine according to the invention, the side wall of the machine being broken away,

2

Fig. 2 is a sectional view illustrating a portion of the lifting mechanism of a guide bar, said view being taken along line 2—2 of Fig. 3, and some parts being broken away,

Fig. 3 is a front elevational view illustrating a portion of the lifting mechanism of a guide bar,

Fig. 4 is a sectional view corresponding to the sectional view shown in Fig. 2, wherein, however, the liftable guide bar is in its elevated position,

Fig. 5 is a sectional view taken along line 5—5 of Fig. 2,

Fig. 6 illustrates a wiring diagram of an electrical system for controlling the main motor and the electrical means for lifting the liftable guide bar of the warp knitting machine shown in Fig. 1,

Fig. 7 is a fragmentary side elevational view of another embodiment of a warp knitting machine according to the invention illustrating the drives of two separate lifting mechanisms,

Figs. 8—10 are sectional views of a switch for controlling the electrical drives of the warp knitting machine according to Fig. 7,

Fig. 11 is a vertical sectional view illustrating the upper portion of the lifting mechanisms of the warp knitting machine shown in Fig. 7, said machine having two liftable guide bars, and

Fig. 12 illustrates a wiring diagram of an electrical system for the control of the main motor and the electrical devices for lifting the guide bars of the warp knitting machine shown in Figs. 7 and 11.

The drawings illustrate only those parts of a warp knitting machine which are necessary for the understanding of the invention.

Referring now to the embodiment of a warp knitting machine shown in Figs. 1—5, 20 generally indicates the frame of a warp knitting machine having a main electro-motor 22 secured to the frame in any suitable manner. The main cam shaft 24, journaled in the frame 20 of the machine, may be driven by the electro-motor 22 through the medium of a belt drive generally indicated by 26. A cam 28 keyed to the main cam shaft 24 cooperates with a cam follower 30 secured to a shaft 32 journaled in the frame 20 of the machine. An arm 34 secured to the rockable shaft 32 is in pivotal connection with one end of a link 36, the other end of which is pivoted at 38 with an arm 40 secured to a rockable guide bar shaft 42 journaled in bearings of the frame 20.

As shown in Figs. 1—5, a series of brackets generally indicated by 44 are fixedly secured in spaced relation to each other to said rockable guide bar shaft 42. Each bracket 44 has a rear downward extension 46 and a front downward extension 48.

In a manner known per se a rear guide bar

50 extending longitudinally of the machine and carrying a row of warp guides 52 is secured to a series of spaced holders generally indicated by 54, only one holder being shown in the drawings. Each holder 54 has a pair of bars 56 slidably engaged with hook-like portions 58 of one of the downward extensions 46 of the spaced brackets 44. Said slidable engagement of the holders 54 with the hook-like portions of the downward extensions of the brackets 44 permits reciprocating displacements of the guide bar 50 in the longitudinal direction of the machine in dependence on a control by a pattern wheel (not shown). As best shown in Fig. 2, the end 60 of each hook-like portion 58 is bent in such a way that it prevents the bars 56 of the holder 54 from an upward movement. In other words, the rear guide bar 50 cannot be lifted relative to the downward extensions 46 of the brackets 44.

As shown in Figs. 1-4 a front guide bar 62 carrying a row of warp guides 64 and extending longitudinally of the machine is secured in a manner known per se to a series of spaced holders 66, only one being shown in said Figs. 1-4. Each holder 66 has a pair of hook-like portions 70 of one of the downward extensions 48 of the spaced brackets 44. The slidable engagement of the holders 66 with the downward extensions 48 of the spaced brackets 44 permits reciprocating movements of the guide bar 62 in the direction of the longitudinal axis of the machine in dependence on the control by the pattern wheel (not shown).

As best shown in Figs. 2 and 4, the hook-like portions 70 of the downward extension 48 of each bracket 44 are open at the top, so that the holder 66 together with the front guide bar 62 attached thereto may be lifted to a certain extent.

For the performance of such a lifting of the front guide bar 62 relative to the bracket 44 and the rear guide bar 50 the following mechanism is arranged in the machine:

A lifting element 72 arranged adjacent the front downward extension of each bracket 44 is provided with two longitudinal slots 74 slidably engaged with bolts 76 inserted into bores 78 of the front downward extension 48 of the bracket 44. Each lifting element 72 has a lifting hook 80 which may come into engagement with the upper bar 68 of the holder 66, when the lifting element 72 is elevated in a manner to be described hereinafter. When the front guide bar 62 is in its lower operating position shown in Fig. 2, the engaging surface 82 of the lifting hook 80 is at a distance from the lower edge of the upper bar 68 of the holder 66. Furthermore, when said lifting element 72 is in its lower position shown in Fig. 2, a lug 84 projecting therefrom is in engagement with the upper edge of the upper bar 68 so as to prevent an undesired lifting of the holder 66 during a reciprocating movement of the front guide bar 62 during the operation of the machine.

As best shown in Figs. 2, 4 and 5 each lifting element carries a roller 86 in engagement with a recess 88 of an arm 90 keyed to a rockable lifter shaft 92 extending longitudinally of the machine and being journaled in bearings 94 (see Fig. 5) of the spaced brackets 44. An arm 96 is keyed to said lifter shaft 92 at a suitable place. The left-hand end of the arm 96 (as viewed in Figs. 1, 2 and 4) is provided with a slot 98 for pivotal and slidable engagement with the upper end of a connecting rod 100. The lower end of said

connecting rod 100 is pivoted to the arm 102 of a lever generally indicated by 104 (see Fig. 1) and keyed to a shaft 106 journaled in suitable bearings of the frame 20 of the machine. The other arm 108 of said lever 104 is arranged for cooperation with the abutting surfaces 110 and 112 of a stop 114 secured to the frame 20 of the machine. A lug 116 carried by the arm 108 of the lever 104 is arranged for cooperation with a spring-loaded plunger of a safety switch 118 mounted on the structure of the stop 114 and electrically connected with the main motor 22.

A sprocket gear 120 keyed to the rockable shaft 106 is operatively connected by means of a chain 122 with a sprocket gear 124 keyed to the shaft 126 of a reversible torque motor 128. The reversible torque motor 128 mounted on the frame 20 of the machine may be operated by means of a shipper rod 130 extending longitudinally of the machine and being journaled for manual rocking movements in suitable bearings of the frame of the machine. The shipper rod 130 acts through an arm 132 on the plunger of a torque motor selector switch 134 electrically connected in a manner to be described hereinafter with the reversible torque motor 128. Preferably, means (not shown) are provided for holding the shipper rod 130 in a set position.

A second shipper rod 136 extending longitudinally of the machine and being journaled in the frame 20 of the latter is arranged for actuating through an arm 138 selectively on a starter switch 140 and a stop switch 142 electrically connected with the main motor 22 of the machine in a manner to be described hereinafter.

Figs. 1, 2 and 3 illustrate the lifting mechanisms 129, 104, 100, 96, 90, 72 and the front guide bar 62 in a position ready for operation of the machine. The warp yarns 144 supplied by the lower warp beam or beams 146 are threaded through the eyelets of the warp guides 52 carried by the rear guide bar 50. The warp yarns 148 supplied by the upper warp beam or beams 150 are threaded through the eyelets of the warp guides 64 carried by the front guide bar 62. When upon actuation of the starter switch 140 by the shipper rod 136 the main motor 22 is energized, the guide bar shaft 42 is oscillated through the drive 26, 28, 30, 34, 36, 40, whereby the bracket 44 carrying the warp guides 50 and 62 are likewise oscillated. Said oscillating movement of the brackets 44 results in an oscillating movement of the arm 96 relative to the connecting rod 100, which is taken up by the slot 98 arranged in said arm 96.

Now, when upon stoppage of the main motor 22 by an actuation of the stop switch 142 by means of the shipper rod 136 the machine is stopped, the reversible torque motor 128 may be caused by an actuation of the torque motor selector switch or actuating switch 134 by means of the shipper rod 130 to rotate in counterclockwise direction (arrow A shown in Fig. 1). Said rotation in counterclockwise direction will result in a downward movement of the connecting rod 100 in the direction of the arrow B, until the arm 108 abuts against the surface 112 of the stop 114. The torque motor 128 remaining under current holds said arm 108 against said abutment 112; at the same time the lug 116 opens the safety switch 118 whereby in a manner to be described hereinafter, the circuit of the main motor 22 is interrupted.

Said downward movement of the connecting rod 100 in the direction of the arrow B causes

5

a rocking of the lifter 92 through the medium of the arm 96 in counterclockwise direction (arrow C shown in Figs. 2 and 4), whereby each arm 90 associated with a lifter element 72 is moved upwardly from the position shown in Fig. 2 into the position shown in Fig. 4. Said upward movement of the arms 90 results in an upward movement of the associated lifter elements 72 from the position shown in Fig. 2 into the position shown in Fig. 4. As soon as the surface 82 of the lifting hook 80 arranged on each lifter element 72 comes into engagement with the upper bar 68 of the associated holder 66, the latter is lifted, so that at the end of this operation the front guide bar 62 and the warp guides 64 carried by the latter reach the lifted or elevated position shown in Fig. 4, which permits access to the warp guides 52 carried by the rear guide bar 50.

When the warp yarn or yarns have been threaded through the eyelet or eyelets of the warp guide or guides 52 of the rear guide bar 50, the front guide bar 62 may be lowered again. For this purpose the torque motor selector switch 134 is actuated by the shipper rod 130 in such a manner that it causes the reversible torque motor 128 to rotate in clockwise direction (arrow D) shown in Fig. 1, whereby the connecting rod 100 is lifted in the direction of the arrow E until the arm 108 of the lever 104 abuts against the surface 110 of the stop 114. The torque motor 128 remaining under current holds said arm 108 against said abutment 110. At the same time the spring loaded plunger of the safety switch 118 following the lug 116 carried by the arm 108 causes the closing of said safety switch 118 arranged in the circuit of the main motor 22. When the connecting rod 100 is lifted in the direction of the arrow E, the lifter rod 92 is rocked in clockwise direction (arrow F shown in Figs. 2 and 4), so that the arms 90 carried by said lifter shaft 92 are returned from the position shown in Fig. 4 into the position shown in Fig. 2. Said downward movement of the arms 90, in turn, results in a downward movement of the lifter element 72 from the position shown in Fig. 4 into the position shown in Fig. 2, whereby likewise the front guide bar 62 carrying the warp guides 64 is returned from its upper inoperative position shown in Fig. 4 into its lower operative position shown in Fig. 2. A spring-loaded bolt 152 (Figs. 2 and 4) carried by each bracket 44 cooperates with a lug 154 of the associated lifter element 72 so as to push same downwardly, if a compensation for the play caused by the slot 98 receiving the upper end of the connecting rod 100 should become necessary.

The electric control system for the main motor 22 and the torque motor or auxiliary motor 128 arranged for lifting and lowering the front guide bar 62 is illustrated in Fig. 6.

A prime circuit, for instance a polyphase circuit 300 is provided that is interconnected to a network 302 fed by an electric source (not shown). The prime circuit 300 has terminals for interconnection to the main motor 22, and has a spring-loaded main switch 304 for connection and disconnection of said main motor. The torque motor 128 admits also of interconnection to the prime circuit 300, at one polarity for operation in one direction to lift the front guide bar 62, and at another polarity for operation in the opposite direction to lower said front guide bar 62. For this purpose, there are provided in the prime circuit 300 a spring-

6

loaded first or lifting switch 306 and a spring-loaded second or lowering switch 308.

Each of the switches 304, 306 and 308 of the prime circuit 300 is provided with a solenoid, the main switch 304 having a solenoid 310, the lifting switch 306 having a solenoid 312 and the lowering switch 308 having a solenoid 314.

The connections between the prime circuit 300 and the terminals associated with the blades of the lifting switch 306 and lowering switch 308 are so arranged, as best shown in Fig. 6, that both switches are biased by springs into lower, open position and actuate the reversible torque motor 128 in the assigned direction of rotation for lifting or lowering the front guide bar 62 by the raising of a switch into upper, closing position under impulse of solenoid action of the solenoids 312 and 314, respectively.

The main switch 304 is normally held by its spring in open position to de-energize the main motor 22, and is closed by means of energization of its solenoid 310. A starter circuit, generally indicated at 316, is interconnected to two of the phase leads of the prime circuit 300, and is interconnected in series to the coil of the solenoid 310, and also to the spring-loaded safety switch 118, to the spring-loaded stop switch 142, and to the spring-loaded starter switch 140. The safety switch 118 and the stop switch 142 are normally held by their springs in closed position, while the starter switch 140 is normally held by its spring in open position. The starter circuit 316 also includes a holding circuit 318 that cooperates with a shunt member 320 of the main switch 304 that moves therewith, and which acts to bridge the starter switch 140 after the main switch 304 has been actuated.

There is provided a spring-loaded control switch 322 that carries a solenoid 324, and the coil of said solenoid 324 is interconnected in series in a control circuit 326 that is arranged in parallel with the solenoid 310 of the main switch 304 and thereby in parallel with a portion of the starter circuit 316. Therefore when current flows through the starter circuit 316, it will also energize the control circuit 326, and thus the solenoids 310 and 324 of the main switch 304 and the control switch 322, respectively, will operate simultaneously to raise and lower (with respect of Fig. 6) these two switches simultaneously.

The control switch or safety switch 322 having two blades 334 and 336 is normally pressed by a spring 332 into the position shown in Fig. 6, wherein its blade 334 bridges terminals in a line of a lifting circuit 328 interconnected in series to the coil of the solenoid 312 of the lifting switch 306 and to two leads of the polyphase prime circuit 300. The terminals 327, 329 in said lifting circuit 328 may be bridged by the torque motor selector switch 134 when the latter is brought by a rocking movement of the shipper rod 130 in clockwise direction (as viewed in Fig. 6) from its lower position shown in Fig. 6 into its upper end position. As will be readily understood, only if the machine is at a standstill, and, consequently, the control switch or safety switch 322 is in its pre-setting position shown in Fig. 6 wherein it closes the lifting circuit by its blade 334, a movement of the selector switch 134 into its upper position bridging the terminals 327, 329 will result in a completion of the lifting circuit 328 causing an energization of the solenoid 312 of the lifting switch 306 and a closing of the latter for an energization of the reversible torque motor 128 to lift the front guide bar 62. However, when

upon a start of the main motor 22 and energization of the solenoid 324 of the control switch 322 the latter is raised from its pre-setting position shown in Fig. 6 into its holding position, wherein its blade 334 interrupts the lifting circuit 328 and its blade 336 closes a holding circuit 338 connected to a lowering circuit 330 to be described hereinafter, the lifting switch 306 cannot be closed by a movement of the torque motor selector switch or actuating switch 134 from the position shown in Fig. 6 into its alternate position wherein it bridges the terminals 327, 329 of the lifting circuit 328.

In the position shown in Fig. 6, the blade of the selector switch 134 bridges the terminals 331, 333 of the lowering circuit 330 interconnected in series to the coil of the solenoid 314 of the lowering switch 308 and to the same two leads of the prime circuit 309 as the lifting circuit 328 (same lines being common to both circuits). Thus, when the machine is at a standstill and, consequently, the control switch 322 is in the position shown in Fig. 6, the lowering circuit 330 is closed when the selector switch 134 is in its lower position shown in said Fig. 6, whereby the solenoid 314 of the lowering switch 308 is energized, thereby closing the latter for an energization of the reversible torque motor 128 to lower the front guide bar 62, until the arm 108 (Fig. 1) of the lever 104 abuts against the abutment 110 of the stop 114, whereupon the torque motor holds said guide bar 62 in its lower operative position.

Upon a start of the motor 22, the solenoid 324 of the control switch or safety switch 322 is energized and the latter is brought from its lower pre-setting position shown in Fig. 6 into its upper holding position wherein it interrupts the lifting circuit 328 at 334 and closes the holding circuit 338 by its blade 336 as mentioned above. Therefore, if during the operation of the machine the selector switch 134 should cause a disconnection of the terminals 331, 333 by an unintentional movement of the shipper rod 130 in clockwise direction, the holding circuit 338 closed by the blade 336 of the control switch 322 and connected with the lowering circuit 330 will permeate the holding down action of the torque motor 128 on the front guide bar 62 against the abutment 110 of the stop 114.

When the selector switch 134 is in its lower position shown in Fig. 6 wherein it bridges the terminals 331, 333 of the lowering circuit 330 and disconnects the terminals 327, 329 of the lifting circuit 328, the lowering switch 308 is in its active or closing position for lowering of the guide bar or holding same down by the torque motor 128, while the lifting switch 306 is in its inactive open position.

When the selector switch 134 is in its alternate upper position wherein it bridges the terminals 327, 329 of the lifting circuit 328 and disconnects the terminals 331, 333 of the lowering circuit 330, the lifting switch 306 is in its active or closing position for lifting the guide bar by the torque motor 128, while the lowering switch 308 is in its inactive position, provided, however, that the machine is at a standstill and the control switch 322 is in its presetting position shown in Fig. 6. If the machine is running and the control switch 322 is in its holding position wherein it interrupts the lifting circuit 328 at 334 and closes the holding circuit 338 at 336, a movement of the selector switch 134 into said alternate position has no influence on the lifting switch 306 which remains

in its inactive open position while the lowering switch 308 is held in its active closing position.

As will be understood from above, the control system includes three safety features: Firstly, the safety switch 118 prevents an operation of the warp knitting machine by the main electro-motor 22 when the front guide bar 62 is in its raised inoperative position. Secondly, the control switch or safety switch 322 prevents a lifting of the front guide bar 62 when the main motor 22 drives the machine. Thirdly, the control switch or safety switch 322 causes a holding down of the front guide bar 62 if, for any reason whatsoever, at the beginning of the machine operation by pressing the starter switch 140 the selector switch 134 is not exactly in its lower closing position shown in Fig. 6, or if, during machine operation the shipper rod 130 is unintentionally rocked causing a slight displacement of the selector switch 134 out of said lower position shown in Fig. 6.

The operation of the warp knitting machine according to Figs. 1-5 equipped with a control system shown in Fig. 6 is as follows:

Assume, the warp yarns are properly threaded and the front guide bar 62 is in its lower operative position shown in Figs. 1-3.

The operator will momentarily rock the shipper rod 136 actuating the starter switch 140 whereby the starter circuit 316 and the control circuit 326 will conduct current, thereby energizing the solenoids 310 and 324 of the main switch 304 and of the control switch 322, respectively. The holding circuit 318 of the starter circuit 316 will permeate this condition (until it is interrupted by the operator pressing the stop switch 142). In this condition, the knitting implements 160 of the machine will be driven by the main motor 22 for the manufacture of fabric 161, and the control switch 322 will be in its holding position wherein the lifting circuit 328 is interrupted at 334 and the holding circuit 338 is closed at 336 so that the lowering switch 308 is held in its closing position and the torque motor 128 is held in energized condition for holding the front guide bar 62 in its lower operative position, even if an unintentional rocking of the shipper rod 130 by the operator occurs which results in a disconnection of the terminals 331, 333 by the selector switch 134.

When a warp yarn breakage occurs, the operator stops the main motor 22 by rocking the shipper rod 136 in the opposite direction causing an actuation of the stop switch 142. Now, the control switch 322, due to the deenergization of its solenoid 324, is in its pre-setting position shown in Fig. 6. In this pre-setting position, the lifting circuit 328 is pre-set for completion by the selector switch 134 in one position thereof.

Now, when the operator, standing in front of the place of warp yarn breakage, rocks the shipper rod 130 for moving the selector switch 134 into the position wherein it bridges the terminals 327, 329 so as to close the lifting circuit 328, the lifting switch 306 is brought into its upper closing position for energizing the reversible torque motor 128 so as to rotate in the direction of the arrow A for lifting the front guide bar 62 into its inoperative position. At the same time the safety switch 118 is automatically opened, so that the main motor 22 cannot be started by an erroneous rocking of the shipper rod 136 actuating the starter switch 140. The torque motor holds the front guide bar 62 in its inoperative raised position permitting repair of a broken warp yarn

and threading thereof through an eyelet of a warp guide 52 of the rear guide bar 50.

Upon completion of the repair of the warp yarn, the operator, who may still stand in front of the place where the warp yarn breakage occurred, may return the shipper rod 130 into its original position for returning the selector switch 134 into the position shown in Fig. 6, wherein it bridges the terminals 331, 333 for closing the lowering circuit 330. Thus, the lowering switch 308 is brought into its upper closing position for energizing the reversible torque motor 128 so as to rotate in the direction of the arrow D for lowering the front guide bar 62 into its operative position and thereafter holding same in said operative position. At the same time, the spring-loaded safety switch 118 is automatically closed, so that the starter circuit 316 is again completed for a restarting of the main motor 22 by closing the starter switch 140 as described above.

It may be noted that owing to the arrangement of the torque motor 128 controlled by the shipper rod 130 extending from end to end of the machine the operator may cause the lifting and lowering of the front guide bar 62 without leaving his position in front of the place where the warp yarn breakage occurred. The lifting and lowering of the guide bar 62 requires merely a rocking of the shipper rod 130 which may be reached at any place.

According to the embodiments shown in Figs. 7-11 the warp knitting machine is equipped with three guide bars 50a, 62a and 162a extending longitudinally of the machine. Again a series of spaced brackets 44a is secured to the rockable guide bar shaft 42a, each bracket having three downward extensions 46a, 48a and 164a. The holder 54a carrying the rear guide bar 50a is slidably engaged with the downward extensions 46a of the brackets 44a in the manner as described above in connection with the holder 54 of the embodiment shown in Figs. 1-5. Therefore, the holder 54a and the rear guide bar 50a cannot be lifted. The holder 66a carrying the intermediate guide bar 62a is slidably engaged with the downward extensions 48a of the brackets 44a and the holder 166a carrying the front guide bar 162a is slidably engaged with the downward extensions 164a of the brackets 44a in the manner as described above in connection with the holder 66 of the embodiment shown in Figs. 1-5. Therefore, the holder 66a with the intermediate guide bar 62a as well as the holder 166a with the front guide bar 162a are liftable.

The linkage 90a, 96a, 100a connected with the lifting elements 72a associated with the holders 66a correspond to the linkage 90, 96, 100 described above in connection with the embodiment shown in Figs. 1-5. As shown in Fig. 7, the lower end of the connecting rod 100a is pivoted to the arm 102a of a double-armed lever 104a secured to a shaft 106a. The other arm 108a of the double-armed lever 104a cooperates with abutments 110a and 112a of a stop 114a secured to the frame 20a of the machine. A lug 116a carried by the arm 108a cooperates with a safety switch 168a mounted on the stop 114a and electrically connected with the main motor 22a driving the knitting implements of the warp knitting machine. The linkage 100a, 90a, 96a may be actuated by means of a reversible torque motor 170a connected with the shaft 106a through a chain drive 172a. The spring-loaded safety switch 168a is automatically opened when the linkage 100a is actuated for lifting the inter-

mediate guide bar 62a with its warp guides 64a into the elevated inoperative position 62a', 64a' shown in dash-and-dot lines in Fig. 11; on the other hand the spring-loaded safety switch 168a is automatically closed as soon as the lug 116a returns into the position shown in Fig. 7, and, consequently, the intermediate guide bar 62a is again in its lower operative position shown in full lines in Fig. 11.

As shown in Fig. 11, each lifting element 174a associated with a liftable holder 166a carrying the front guide bar 162a is pivotally connected with the lower end of a link 176a the upper end of which is pivoted to an arm 178a secured to a lifter shaft 180a journalled in bearings of the brackets 44a. An arm 182a fixedly secured to said lifter shaft 180a is pivotally and slidably engaged at 184a with the upper end of a connecting rod 186a. As shown in Fig. 7 the lower end of said connecting rod 186a is pivotally connected with the arm 188a of a double-armed lever 190a secured to a shaft 192a journalled in the frame 20a. The other arm 194a of said lever 190a is arranged for cooperation with abutments 196a and 198a of a stop 200a mounted on the frame of the machine. A lug 202a arranged for cooperation with the spring-loaded plunger of a safety switch 118a is carried by the arm 194a of the lever 190a. The safety switch 118a mounted on the stop 200a is electrically connected with the main motor 22a. A sprocket gear 204a keyed to the shaft 192a may be rotated in counter-clockwise and clockwise direction by means of a reversible torque motor 128a mounted on the frame of the machine and connected with said sprocket gear 204a by means of a chain 206a.

As will be readily understood, when the torque motor 128a is switched on for rotation in counter-clockwise direction (arrow G in Fig. 7), the connecting rod 186a is moved downwardly in the direction of the arrow H with the results, that the arm 178a, the lifting elements 174a, the holder 166a and the front guide bar 162a with the warp guides 208a mounted thereon are elevated into the lifted positions 178a', 174a', 160a', 162a' and 208a', respectively. The downward movement of the connecting rod 186a is limited by an abutment of the arm 194a against the surface 198a of the stop 200a. The torque motor 128a holds the guide bar 162a in its inoperative elevated position 162a' as long as it is energized for rotation in the direction of the arrow G. The lug 202a holds the safety switch 118a in open position.

When thereafter the torque motor 128a is energized for rotation in clockwise direction (arrow K shown in Fig. 7), the connecting rod 186a is lifted in the direction of the arrow L until the arm 194a abuts against the surface 196a of the stop 200a, whereby the front guide bar 162a is returned into its operative position shown in full lines in Fig. 11. As long as the torque motor 128a is energized for rotation in the direction of the arrow K it holds the front guide bar 162a in its lower inoperative position. Upon return of the arm 194a and the lug 202a mounted thereon into the lower position shown in Fig. 7, the spring-loaded safety switch 118a is automatically closed.

As will be described hereinafter the operation of the torque motors 128a and 170a actuating the linkages for lifting and lowering the front guide bar 162a and intermediate guide bar 62a is controlled by a torque motor selector switch or actuating switch 134a, which in turn may be

actuated by a manual rocking of a shipper rod 130a extending longitudinally of the machine. A second shipper rod 136a extending longitudinally of the machine is arranged for actuation of a starter switch 142a electrically connected with the main motor 22a for starting and stopping the operation of the latter. The electrical control system used in conjunction with a warp knitting machine having three guide bars according to the embodiment of Figs. 7-11 is as follows:

Both torque motors or auxiliary motors 128a and 170a are controlled by the single three-way selector switch 134a.

Similar to the previously described embodiment there is again provided a prime circuit 300a interconnected to a network 302a, a main switch 304a that actuates the main motor 22a; there is again a starter circuit 316a that has, however, in series not only one safety switch, but two spring-loaded safety switches 118a and 168a, operated respectively, by the levers 190a and 184a (Fig. 7) of the lifting mechanisms connected with the torque motors 128a and 170a (Figs. 7 and 12). The spring-loaded starter switch 140a and the spring-loaded stop switch 142a are arranged in the starter circuit 316a, and there is also provided a holding circuit 318a cooperating with a shunt member 320a of the main switch 304a to hold the starter circuit 316a closed. A control switch 322a is again energizable by a control circuit 326a that is arranged in parallel with the coil of the main switch solenoid 310a.

A control switch or safety switch 322a has a solenoid 324a in series with the control circuit 326a and is provided with a tension-spring 332a, and three blades, a lower blade 334a, a middle blade 336a and an upper blade 337a. Each of the torque motors is provided with a lifting switch and with a lowering switch, for interconnection of each torque motor, at selectively alternate running directions, to the prime circuit 300a. The torque motor 128a associated with the front guide bar 162a is provided with a lifting switch 306a and a lowering switch 308a having solenoids 312a and 314a respectively; and the torque motor 170a associated with the intermediate guide bar 62a is provided with a lifting switch 307a having a solenoid 313a, and a lowering switch 309a having a solenoid 315a.

A lifting circuit 328a and a lowering circuit 330a are again provided and are interconnected to the switches of both torque motors, and the selector switch 134a is so arranged in the circuits that it can alternately switch to lifting and lowering of the liftable guide bars. On lifting, the torque motor 128a is operated first, so that the front guide bar 162a is lifted first, whereas on lowering, the torque motor 128a and consequently the guide bar 162a are operated last.

A holding circuit 338a again is provided to hold the lowering circuit 330a closed when the machine is running and the control switch 322a is in its holding position wherein its middle blade 336a closes said holding circuit 338a and its upper blade 337a bridges the terminals 340a and 342a of the lowering circuit 330a, so that upon an unintentional disconnection of the terminals 331a, 333a and 344a and 346a of the lowering circuit 330a by the selector switch 134a the lowering circuit 330a remains closed and the front and intermediate guide bars 162a and 62a are held in their operative positions by the torque motors 128a and 170a. Furthermore, when said control switch 322a is in said holding position, it interrupts the lifting circuit 328a at 334a to pre-

vent guide bar lifting while the machine is running.

On the other hand, when the machine is at a standstill and the control switch 322a is in its pre-setting position shown in Fig. 12, its lower blade 334a closes the lifting circuit 328a, while its middle blade 336a interrupts the holding circuit 338a and its upper blade 337a interrupts the lowering circuit 330a.

10 As in the previous embodiment, the switches for the torque motors are so arranged in the prime circuit 300a as shown in Fig. 12, that the motors are connected at one polarity during lifting switch operation, to operate in the guide bar lifting direction, and at changed polarity during lowering switch operation to operate in an opposite direction for guide bar lowering.

A first bridge 362a of the selector switch 134a is arranged for cooperation with the terminals 331a and 333a of the lowering circuit 330a for the lowering switch 308a of the first torque motor 128a and for cooperation with terminals 327a, 329a of the lifting circuit 328a for the lifting switch 306a of the same torque motor 128a. A second bridge 366a of said selector switch 134a is arranged for cooperation with the terminals 344a and 346a of the lowering circuit 330a for the lowering switch 308a of the second torque motor 170a and for cooperation with terminals 352a, 354a of the lifting circuit 328a for the lifting switch 307a of the same torque motor 170a.

As shown in Figs. 7-12, the selector switch 134a comprises an arm 356a that is mounted about midway of its length on the shipper rod 130a, and is rockable by the shipper rod in opposite directions. An adjustable screw 358a is mounted near one end of the arm, and another screw 360a is mounted near the other end of the arm.

The first bridge 362a of the selector switch 134a is movably arranged opposite one of the arm ends and is arranged to interconnect the terminals 331a and 333a in one position (see Fig. 8), and to interconnect the terminals 327a and 329a in the second position, (see Fig. 9), and is pressed towards said second position by a spring 364a.

The second bridge 366a of the selector switch 134a is movably arranged opposite the other end of the arm 356a, and is arranged to interconnect in one position the terminal 344a with the terminal 346a (see Fig. 8), and to interconnect the terminal 352a with the terminal 354a in its second position (see Fig. 10), and is pressed into said first position by a spring 368a. Each bridge carries a projection for operation by a screw of the arm 356a, the bridge 362a being operated by the screw 358a, and the bridge 366a being operated by the screw 360a.

Thus, when the arm 356a is in the position shown in Fig. 8, the terminals 331a and 333a are interconnected by the bridge 362a under the action of the screw 358a, whereby the lowering switch 308a of the torque motor 128a is actuated for lowering the front guide bar 162a into its operative position or holding same in the latter respectively. In this position, the other screw 360a releases the second bridge 366a and the latter is pressed by the spring 368a to make contact with the terminals 344a and 346a, to close the lowering switch 309a of the torque motor 170a for lowering the intermediate guide bar 62a into its operative position, or holding same in the latter respectively. This may be termed the first position.

A second position is shown in Fig. 10, where the arm 356a is rocked so that both bridges are

released by the screws and are both under action of the springs 364a and 368a, respectively. In this second position, when the control switch 322a is in its pre-setting position (shown in Fig. 12), the lifting switch 306a of the torque motor 128a is operated for lifting of the front guide bar 162a, and the lowering switch 309a of the other torque motor 170a is still operated for holding the intermediate guide bar 62a in its operative position.

In a third position, illustrated in Fig. 10, the arm 358a is rocked in position for operation of the bridge 366a by the screw 360a against the power of the spring 368a, and the bridge 362a is under action of the spring 364a. This connects both lifting switches 308a and 309a to the electric source, when the control switch 322a is in its pre-setting position of Fig. 12, and the front guide bar 162a as well as the intermediate guide bar 62a are thus lifted.

The shipper rod 130a may be held in each of said three positions shown in Figs. 8-10 by means of a suitable device. For example, the shipper rod 130a may be rigidly connected with an index disc having three recesses for cooperation with a spring-loaded holding member capable of engagement with one recess or another.

The operation of a warp knitting machine according to Figs. 7-11 equipped with an electric control system shown in Fig. 12 is as follows:

Assume, the warp yarns are properly threaded and the front guide bar 162a as well as the intermediate guide bar 62a are in their lower operative position shown in full lines in Fig. 11.

Upon actuation of the starter switch 140a, the main motor 22a drives the knitting implements 160a of the machine. At the same time the control switch or safety switch 322a is brought into its holding position wherein its blade 334a interrupts the lifting circuit 328a and its blades 336a and 337a close the holding circuit 338a and the lowering circuit 330a respectively.

When a warp yarn threaded through an eyelet of a warp guide 64a carried by the intermediate guide bar 62a breaks, the operator stops the main motor 22a by an actuation of the stop switch 142a by means of a rocking of the shipper rod 136a, whereby the control switch 322a will also be returned into its pre-setting position shown in Fig. 12. In said pre-setting position the lifting circuit 328a is pre-set for completion by the selector switch 134a. Now, when the operator rocks the second shipper rod 130a from the position shown in Fig. 8 into the position shown in Fig. 9, the torque motor selector switch 134a completes the lifting circuit for the lifting switch 306a causing an operation of the torque motor 128a for rotation in counterclockwise direction (arrow G), while the lowering switch 309a for the torque motor 170a remains closed. Therefore, only the front guide bar 162a is lifted into the inoperative raised position 162a', while the intermediate guide bar 62a remains in its operative position. Upon lifting of the front guide bar 162a the warp guides 64a carried by the intermediate guide bar 62a become accessible for rethreading of the broken warp yarn.

After repair of the broken warp yarn the shipper rod 130a is returned from the position shown in Fig. 9 into the position shown in Fig. 8, whereby the torque motor selector switch 134a interrupting the lifting circuit 328a for the lifting switch 306a and closing the lowering circuit 330a for the lowering switch 308a causes a lowering of the front guide bar 162a into its lower opera-

tive position, so that the machine is ready for re-starting.

If a warp yarn threaded through the eyelet 52a carried by the rear guide bar 50a should break, the operator at first brings the shipper rod 130a from the position shown in Figs. 7 and 8 into the position shown in Fig. 9, and thereafter into the position shown in Fig. 10, whereby the torque motor selector switch 134a completes at first the lifting circuit for the lifting switch 306a, causing a lifting of the front guide bar 162a by the torque motor 128a into its raised inoperative position 162a', and completes thereafter the lifting circuit for the lifting switch 307a causing a lifting of the intermediate guide bar 62a by the torque motor 170a into its raised inoperative position 62a', so that the warp guides 52a carried by the rear guide bar 50a become accessible. After the performance of the necessary repairs and the re-threading of the warp yarn or warp yarns through the eyelet or eyelets of a warp guide or warp guides carried by the rear guide bar 50a, the shipper rod 130a is returned from the position shown in Fig. 10 through the position shown in Fig. 9 into the position shown in Fig. 8, whereby at first the intermediate guide bar 62a and thereafter the front guide bar 162a are returned into their lower operative positions, and the machine is ready for restarting. As the lowering circuits for the lowering switch 308a and for the lowering switch 309a are closed by the selector switch 134a in the position of Fig. 8, the front guide bar 162a as well as the intermediate guide bar 62a are held in their lower operative positions by the torque motors 128a and 170a respectively.

The control system shown in Fig. 12 also includes three safety features: Firstly, the safety switches 118a and 168a prevent an operation of the warp knitting machine by the motor 22a when either the front guide bar 162a or the front guide bar 162a and the intermediate guide bar 62a are in raised inoperative position. Secondly, the control switch or safety switch 322a prevents a lifting of the guide bars 62a and 162a when the main motor 22a drives the machine. Thirdly, the control switch or safety switch 322a causes a holding down of the front guide bar 162a and the intermediate guide bar 62a when at the start of the machine the selector switch 134a is not exactly in the position shown in Fig. 8 or when the machine is running and the shipper rod 130a associated with the selector switch 134a is unintentionally rocked.

It is understood that the described lifting of the guide bar or guide bars of a warp knitting machine by the mechanisms and arrangements according to the invention may also be used for threading all of the warp yarns of the warp beams when the machine shall be made ready for operation.

I have described preferred embodiments of my invention, but it is understood that this disclosure is for the purpose of illustration and that various omissions or changes in shape, proportion and arrangement of parts, as well as the substitution of equivalent elements for those herein shown and described may be made without departing from the spirit and scope of the invention as set forth in the appended claims.

For example, instead of a reversible torque motor, a non-reversible torque motor could be used for actuating the lifting mechanism of a guide bar; in such a case, the guide bar would be lifted by an energization of the torque motor,

while upon de-energization of the torque motor the lowering of the guide bar would take place by the action of its own weight, perhaps assisted by the action of a return spring connected with an element of the lifting mechanism.

Furthermore, instead of a torque motor another suitable electrical device could be used for actuating the lifting mechanism of a guide bar, for example another type of an electromotor, or an electromagnetic device.

If desired, the electric control system may also be modified, for example one or the other safety device could be omitted.

Moreover, if desired, the electric means for actuating the lifting mechanism of a guide bar could be replaced by non-electrical power means. For example, a hydraulic or mechanical drive, which may be rendered active or inactive by an actuating element readily accessible from any place in front of the warp knitting machine could be used; in such a case, preferably, the actuating element is in the shape of a rod or bar extending longitudinally of the machine and being arranged for causing or stopping an operation of the hydraulic or mechanical drive.

What I claim is:

1. In a warp knitting machine the combination of: a rockable guide bar shaft, a series of spaced brackets secured to said guide bar shaft, a plurality of guide bars extending longitudinally of the machine, said guide bars being suspended from said brackets, at least one of said guide bars being slidably mounted on its associated brackets for lifting movement from a lower operative end position into an upper inoperative end position, a lifting mechanism associated with said liftable guide bar for displacing same from one end position into the other one, and controllable power means associated with said lifting mechanism for actuating the latter.

2. In a warp knitting machine the combination of: a rockable guide bar shaft, a series of spaced brackets secured to said guide bar shaft, a plurality of guide bars extending longitudinally of the machine, said guide bars being suspended from said brackets, at least one of said guide bars being slidably mounted on its associated brackets for lifting movement from a lower operative end position into an upper inoperative end position, a lifting mechanism associated with said liftable guide bar for displacing same from one end position into the other one, controllable power means associated with said lifting mechanism for actuating the latter, and a manually operable actuating element extending longitudinally of the machine, said actuating element being associated with said power means for controlling the operation of the latter.

3. In a warp knitting machine the combination of: a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, and controllable power means associated with said lifting mechanism for actuating the latter, said power means being operable for lifting and lowering said guide bar, and said power means being operable for holding said guide bar in its lower operative position by the force of the output generated by said power means.

4. In a warp knitting machine the combination of: a main drive for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, controllable power means associated with said lifting mechanism for actuating the latter, and a safety device responsive to the position of said liftable guide bar and included in said main drive for disabling the latter when said liftable guide bar is in its inoperative position.

5. In a warp knitting machine the combination of: a main drive for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, controllable power means associated with said lifting mechanism for actuating the latter, a first safety device responsive to the position of said liftable guide bar and associated with said main drive for rendering the latter inoperative when said liftable guide bar is in its inoperative position, and a second safety device responsive to the operation of said main drive and associated with said power means for preventing the latter from actuating the lifting mechanism for a lifting of said guide bar when said main drive is in operation for driving the machine.

6. In a warp knitting machine the combination of: a main drive for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, controllable power means associated with said lifting mechanism for actuating the latter, said power means being operable for lifting and lowering said guide bar and for holding same in its lower operative position, and a safety device responsive to the operation of said main drive and associated with said power means for operating same to hold said guide bar in its operative position when said main drive is in operation for driving the machine.

7. In a warp knitting machine the combination of: a main drive for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, controllable power means associated with said lifting mechanism for actuating the latter, said power means being operable for lifting and lowering said guide bar, and said power means being operable for holding said guide bar in its lower operative position by the force of the output generated by said power means.

said guide bar and for holding the latter in its operative position, settable conditioning means associated with said power means for controlling the operation of the latter, and a safety device responsive to the operation of said main drive and associated with said conditioning means for retaining same in a conditioning position for an operaton of said power means to hold said guide bar in its lower operative position when said main drive is in operation for driving the machine.

8. In a warp knitting machine the combination of: a main drive for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, controllable power means associated with said lifting means for actuating the latter, said power means being operable for lifting and lowering said guide bar and for holding the latter in its operative position, settable conditioning means associated with said power means for controlling the operation of the latter, a first safety device responsive to the position of said liftable guide bar and associated with said main drive for rendering the latter inoperative when said liftable guide bar is in its inoperative position, a second safety device responsive to the operation of said main drive and associated with said conditioning means for preventing a conditioning position thereof for an operation of said power means causing a lifting of said guide bar when said main drive is in operation for driving the machine, and a third safety device responsive to the operation of said main drive and associated with said conditioning means for retaining same in a conditioning positon for an operaton of said power means to hold said guide bar in its lower operative position when said main drive is in operation for driving the machine.

9. In a warp knitting machine the combination of: a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, electric means associated with said lifting mechanism for actuating the latter, switch means electrically connected with said electric means, and a rockable shipper rod extending longitudinally of the machine, said shipper rod being associated with said switch means for controlling same.

10. In a warp knitting machine the combination of: a rockable guide bar shaft, a series of spaced brackets secured to said guide bar shaft, a plurality of guide bars extending longitudinally of the machine, said guide bars being suspended from said brackets, at least one of said guide bars being slidably mounted on its associated brackets for lifting movement from a lower operative end position into an upper inoperative end position, a lifting mechanism associated with said liftable guide bar for displacing same from one end position into the other one, a reversible

torque motor associated with said lifting mechanism for actuating the latter so as to lift and lower said guide bar, and limiting means arranged for cooperation with said lifting mechanism for limiting end positions thereof against the action of said torque motor.

11. In a warp knitting machine the combination of: a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, an electric motor associated with said lifting mechanism for actuating the latter, switch means electrically connected with said electric motor, and a rockable shipper rod extending longitudinally of the machine, said shipper rod being associated with said switch means for controlling same.

12. In a warp knitting machine the combination of: a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, a reversible torque motor associated with said lifting mechanism for actuating the latter so as to lift and lower said guide bar, limiting means arranged for cooperation with said lifting mechanism for limiting end positions thereof against the action of said torque motor switch means electrically connected with said torque motor, and a rockable shipper rod extending longitudinally of the machine, said shipper rod being associated with said switch means for controlling same.

13. In a warp knitting machine the combination of: a main electromotor for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, electric means associated with said lifting mechanism for actuating the latter, a safety switch, and a motor circuit including said main electromotor and said safety switch, said safety switch being responsive to the position of said liftable guide bar for interrupting said motor circuit when said liftable guide bar is in its inoperative position.

14. In a warp knitting machine as claimed in claim 13, said lifting mechanism being operatively associated with said safety switch for opening same when said guide bar is in its inoperative position.

15. In a warp knitting machine the combination of: a main electromotor for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative

position, a lifting mechanism associated with said liftable guide bar for displacing same, electric means associated with said lifting mechanism for actuating the latter, a first switch electrically connected with said electric means and operable for connecting same with an electric source so as to cause a lifting of said guide bar, and a safety switch electrically connected with said first switch and responsive to the operation of said main electromotor for preventing said first switch from connecting said electric means with said electric source when said main electromotor is in operation for driving the machine.

16. In a warp knitting machine the combination of: a main electromotor for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, electric means associated with said lifting mechanism for actuating the latter, a first safety switch, a motor circuit including said main electromotor and said first safety switch, said first safety switch being responsive to the position of said liftable guide bar for interrupting said motor circuit when said liftable guide bar is in its inoperative position, a first switch electrically connected with said electric means and operable for connecting same with an electric source so as to cause a lifting of said guide bar, and a second safety switch electrically connected with said first switch and responsive to the operation of said main electromotor for preventing said first switch from connecting said electric means with said electric source when said main electromotor is in operation for driving the machine.

17. In a warp knitting machine the combination of: a main electromotor for operating the machine, a rockable guide bar shaft, a series of spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, a reversible auxiliary motor associated with said lifting mechanism for actuating the latter, said reversible motor being operable in one direction of rotation for lifting said guide bar and being operable in the other direction of rotation for lowering said guide bar and for holding same in its operative position, a first switch electrically connected with said reversible auxiliary motor and operable for connecting same with an electric source so as to cause a lifting of said guide bar, a second switch electrically connected with said reversible auxiliary motor and operable for connecting same with said electric source so as to cause a lowering of said guide bar and holding same in its operative position, and a safety switch responsive to the operation of said main electromotor and electrically connected with said second switch for holding same in connecting position when said main electromotor is in operation for driving the machine.

18. In a warp knitting machine the combination of: a main electromotor for operating the machine, a rockable guide bar shaft, a series of

spaced brackets secured to said guide bar shaft, a plurality of guide bars extending longitudinally of the machine, said guide bars being suspended from said brackets, at least one of said guide bars being liftable relative to said brackets from a lower operative position into an upper inoperative position, a lifting mechanism associated with said liftable guide bar for displacing same, a reversible auxiliary motor associated with said lifting mechanism for actuating the latter, said reversible motor being operable in one direction of rotation for lifting said guide bar and being operable in the other direction of rotation for lowering said guide bar and for holding same in its operative position, a first switch electrically connected with said reversible auxiliary motor and operable for connecting same with an electric source so as to cause a lifting of said guide bar, a second switch electrically connected with said reversible auxiliary motor and operable for connecting same with said electric source so as to cause a lowering of said guide bar and holding same in its operative position, a first safety switch, a motor circuit including said main electromotor and said first safety switch, said first safety switch being responsive to the position of said liftable guide bar for interrupting said motor circuit when said liftable guide bar is in its inoperative position, a second safety switch electrically connected with said first switch and responsive to the operation of said main electromotor for preventing said first switch from connecting said electric means with said electric source when said main motor is in operation for driving the machine, and a third safety switch responsive to the operation of said main electromotor and electrically connected with said second switch for holding same in connecting position when said main electromotor is in operation for driving the machine.

19. In an electric control system, for use in connection with a warp knitting machine having at least one liftable guide bar, an electric main motor for machine operation and at least one electrical device operable for guide bar lifting operation, in combination with: an electric circuit comprising main motor actuating means, means for energizing said electrical device, and control means responsive to said actuating means for pre-setting said energizing means to restrain energization of said electrical device during main motor actuation.

20. In an electric control system, for use in connection with a warp knitting machine having at least one liftable guide bar, an electric main motor for machine operation and at least one electrical device operable in opposite direction for guide bar lifting and lowering, in combination with: an electric circuit comprising main motor actuating means, means for alternately oppositely energizing said electrical device, selecting means for said energizing means to select the direction of operation of said electrical device, and control means responsive to said actuating means for pre-setting said energizing means to restrain energization of said electrical device in one direction during main motor actuation.

21. In an electric control system, for use in connection with a warp knitting machine having at least one liftable guide bar, an electric main motor for machine operation and at least one electrical device operable in opposite directions for guide bar lifting and lowering, in combination with: an electric circuit comprising main motor actuating means, means for alter-

nately oppositely energizing said electrical device, selecting means for said energizing means to select the direction of operation of said electrical device, and control means responsive to said actuating means for pre-setting said energizing means to restrain energization of said electrical device in one direction and for maintaining energization of said electrical device in the other direction during main motor actuation.

22. In an electric control system, for use in connection with a warp knitting machine having at least one liftable guide bar, an electric main motor for machine operation and at least one electrical device operable for guide bar lifting, in combination: a prime circuit for said motor and for said electrical device interconnected to an electric source and comprising a normally open main switch movable for connection of said main motor to said prime circuit, and a lifting switch normally open and operable for interconnecting said electrical device to said prime circuit for guide bar lifting; a starter circuit including a solenoid for said main switch and a manually actuatable starter switch for operation of said solenoid to close said main switch for machine operation; a lifting circuit including a solenoid for said lifting switch and being normally interrupted to hold open said lifting switch; an actuating switch manually movable for completing said lifting circuit; a control switch biased towards a first position of pre-setting said lifting circuit for completion by said actuating switch and being movable to a second position of interrupting said lifting circuit for restraining guide bar lifting; and a control circuit connected to said starter circuit and including a solenoid for said control switch for movement thereof to said second position during main motor energization.

23. In an electric control system, for use in connection with a warp knitting machine having at least one liftable guide bar, an electric main motor for machine operation and at least one electrical device operable in opposite directions for guide bar lifting and lowering, in combination: a prime circuit for said motor and for said electrical device interconnected to an electric source and comprising a normally open main switch movable for connection of said main motor to said prime circuit, a lifting switch normally open and operable for interconnecting said electrical device to said prime circuit to operate in one direction for guide bar lifting, and a lowering switch for interconnecting said electrical device to said prime circuit at changed polarity to operate in the opposite direction for guide bar lowering; a starter circuit including a solenoid for said main switch and a manually actuatable starter switch for operation of said solenoid to close said main switch for machine operation; a lifting circuit including a solenoid for said lifting switch and being normally interrupted to hold open said lifting switch; a lowering circuit including a solenoid for said lowering switch; a selector switch manually movable between at least two positions for alternately completing one among said lifting and lowering circuits; a control switch biased towards a first position of pre-setting said lifting circuit for completion by said selector switch and being movable to a second position of interrupting said lifting circuit for restraining guide bar lifting; and a control circuit connected to said starter circuit and including a solenoid for said control

switch for movement thereof to said second position during main motor energization.

24. In an electric control system, for use in connection with a warp knitting machine having at least one liftable guide bar, an electric main motor for machine operation and at least one electrical device operable in opposite directions for guide bar lifting and lowering, in combination: a prime circuit for said motor and for said electrical device interconnected to an electric source and comprising a normally open main switch movable for connection of said main motor to said prime circuit, a lifting switch normally open and operable for interconnecting said electrical device to said prime circuit to operate in one direction for guide bar lifting, and a lowering switch for interconnecting said electrical device to said prime circuit at changed polarity to operate in the opposite direction for guide bar lowering, a starter circuit including a solenoid for said main switch and a manually actuatable starter switch for operation of said solenoid to close said main switch for machine operation; a lifting circuit including a solenoid for said lifting switch and being normally interrupted to hold open said lifting switch; a lowering circuit including a solenoid for said lowering switch; a selector switch manually movable between at least two positions for alternately completing one among said lifting and lowering circuits; a control switch biased towards a first position of pre-setting said lifting circuit for completion by said selector switch and being movable to a second position of interrupting said lifting circuit to restrain guide bar lifting and of simultaneously closing said lowering circuit for guide bar lowering; and a control circuit connected to said starter circuit and including a solenoid for said control switch for movement thereof to said second position during main motor energization and for release to return to said first position when said main motor is deenergized.

25. In an electric control system, for use in connection with a warp knitting machine having at least one guide bar liftable from and lowerable to a normal operative position, an electric main motor for machine operation, and at least one reversible torque motor for guide bar lifting and lowering, in combination: a prime circuit for said motors interconnected to an electric source and comprising a normally open main switch movable for connection of said main motor to said prime circuit, a lifting switch normally open and operable for interconnecting said torque motor to said prime circuit to rotate in one direction for guide bar lifting, and a lowering switch for interconnecting said torque motor to said prime circuit at changed polarity to rotate in the opposite direction for guide bar lowering; a starter circuit including a solenoid for said main switch and a manually actuatable starter switch for operation of said solenoid to close said main switch for machine operation; a lifting circuit including a solenoid for said lifting switch and being normally interrupted to hold open said lifting switch; a lowering circuit including a solenoid for said lowering switch; a selector switch manually movable between at least two positions of alternately completing one among said lifting and lowering circuits; a control switch biased towards a first position of pre-setting said lifting circuit for completion by said selector switch and being movable to a second position of interrupting said lifting circuit to restrain guide

bar lifting and of simultaneously closing said lowering circuit for guide bar lowering; and a control circuit connected in parallel with a portion of said starter circuit and including a solenoid for said control switch for movement thereof to said second position during main motor energization, and for release to return to said first position when said main motor is deenergized, whereby guide bar lifting can take place only at machine standstill and said guide bar will be maintained in operative position during machine operation.

26. In an electric control system as claimed in claim 22, together with, a normally closed safety switch in said starter circuit, and means operable by said electrical device, upon energization thereof for guide bar lifting, to open said safety switch.

27. In an electric control system, for use in connection with a warp knitting machine having a plurality of liftable guide bars, and electric main motor for machine operation, and a plurality of electrical devices, each associated with a guide bar and operable for lifting thereof, in combination: a prime circuit for said motor and for said electrical device, interconnected to an electric source and comprising a normally open main switch movable for connection of said main motor to said prime circuit, and a lifting switch for each electrical device normally open and operable for interconnecting said electrical device to said prime circuit for guide bar lifting; a starter circuit including a solenoid for said main switch and a manually actuatable starter switch for operation of said solenoid to close said main switch for machine operation; a lifting circuit including a solenoid for each lifting switch and being normally interrupted to hold open said lifting switches; an actuating switch manually movable for completing at least a portion of said lifting circuit to lift at least one guide bar; a control switch biased towards a first position of pre-setting said lifting circuit for completion by said actuating switch and being movable to a second position of interrupting said lifting circuit for restraining guide bar lifting; and a control circuit connected to said starter circuit and including a solenoid for said control switch for movement thereof to said second position during main motor energization.

28. In an electric control system as claimed in claim 27, together with, at least one normally closed safety switch in said starter circuit, and means operable by said electrical devices, upon energization thereof for guide bar lifting, to open said safety switch.

29. In an electric control system for use in connection with a warp knitting machine having a plurality of guide bars each liftable from and lowerable to a normal operative position, an electric main motor for machine operation, and a plurality of reversible torque motors each associated with a guide bar and operable for lifting and lowering same, in combination: a prime circuit for said motors interconnected to an electric source and comprising a normally open main switch movable for connection of said main motor to said prime circuit, a lifting switch for each torque motor normally open and operable for interconnecting said torque motor to said prime circuit to rotate in one direction for guide bar lifting, and a lowering switch for each torque motor for interconnecting said torque motor to said prime circuit at changed polarity to rotate in the opposite direction for guide bar lowering; a starter

circuit including a solenoid for said main switch and a manually actuatable starter switch for operation of said solenoid to close said main switch for machine operation; a lifting circuit including branches having each a solenoid for a lifting switch and being normally interrupted to hold open said lifting switches, a lowering circuit including branches having each a solenoid for a lowering switch; a selector switch manually movable between at least two positions of alternately completing at least one of the branches of said lifting and lowering circuit, respectively; a control switch biased towards a first position for pre-setting said lifting circuit for at least partial completion by said selector switch to lift at least one guide bar and being movable to a second position of interrupting said lifting circuit to restrain guide bar lifting; and a control circuit connected in parallel with a portion of said starter circuit and including a solenoid for said control switch for movement thereof to said second position during main motor energization.

30. In an electric control system as claimed in claim 29, said machine having two guide bars liftable in a predetermined sequence and lowerable in reversed sequence, said lifting and lowering circuits having each two branches, said selector switch being movable between three successive positions for controlling said sequence, in the first position of said selector switch both branches of said lowering circuit being closed, in the intermediate position of said selector switch one branch of the lifting circuit coordinated with the firstly liftable guide bar being closed and one branch of the lowering circuit coordinated with the secondly liftable guide bar being closed, and in the third position of said selector switch both branches of said lowering circuit being closed.

31. In an electric control system, for use in connection with a warp knitting machine having a plurality of guide bars each liftable from and lowerable to a normal operative position, an electric main motor for machine operation, and a plurality of reversible torque motors each associated with a guide bar and operable for lifting and lowering same, in combination: a prime circuit for said motors interconnected to an electric source and comprising a normally open main switch movable for connection of said main motor to said prime circuit, a lifting switch for each torque motor normally open and operable for interconnecting said torque motor to said prime circuit to rotate in one direction for guide bar lifting, and a lowering switch for each torque motor for interconnecting said torque motor to said prime circuit at changed polarity to rotate in the opposite direction for guide bar lowering; a starter circuit including a solenoid for said main switch and a manually actuatable starter switch for operation of said solenoid to close said main switch for machine operation; a lifting circuit including branches having each a solenoid for a lifting switch and being normally interrupted to hold open said lifting switches, a lowering circuit including branches having each a solenoid for a lowering switch; a selector switch manually movable between at least two positions of alternately completing at least one of the branches of said lifting and lowering circuits, respectively; a control switch biased towards a first position of pre-setting said lifting circuit for at least partial completion by said selector switch to lift at least one guide bar and being movable to a second position of inter-

rupting said lifting circuit to restrain guide bar lifting and of simultaneously closing said lowering circuit for lowering said guide bars; and a control circuit connected in parallel with a portion of said starter circuit and including a solenoid for said control switch for movement thereof to said second position during main motor energization, and for release to return to said first position when said main motor is deenergized, whereby guide bar lifting can take place only at machine standstill and all of said guide bars will be maintained in operative position during machine operation.
